APPARATUS FOR TESTING GOLF BALLS

Philip E. Young, Fairhaven, Mass., assignor to
Acushnet Process Company, a corporation of
Massachusetts

Application May 4, 1936, Serial No. 77,718

14 Claims. (Cl. 73—51)

This invention relates to golf ball testing apparatus which preferably has a plurality of rotatably mounted driving arms which are adapted to strike golf balls for purposes of comparison or demonstration. The golf balls to be tested are placed on rotating feed arms, the speed of the driving arms and feed arms being synchronized so that each golf ball will be in correct position to be accurately struck by the driving arm as the driving arm moves to this position. I may use a manual or automatic feeding device in connection with each feed arm. As shown in the drawings I provide a feed device for each feed arm which includes a lever adapted to hold a golf ball. The lever is mounted so that it rotates with the feed arm for a portion of the rotation of the feed arm and deposits the golf ball on the feed arm after which the lever is returned to its original position ready for the next actuation. In this way the driving arms are simultaneously rotated continuously to simultaneously strike golf balls and sets of comparative tests may be made. My apparatus may be used to test golf clubs or the like instead of golf balls or the like. I may use an apparatus for testing golf balls or golf clubs of a greater number than two.

My apparatus may be driven by electricity or from the crankshaft of an engine of an automobile. The apparatus is of such size that it may be easily transported from place to place to give exhibitions of comparative tests and for this purpose may be mounted on a truck or on a trailer attached to a motor vehicle. Screens or guards may be used on the sides of the apparatus to protect against accidents.

In the drawings:

Fig. 1 represents a front elevation of one embodiment of my invention;

Fig. 2 represents a side elevation of the device shown in Fig. 1;

Fig. 3 represents a top plan view with the driving arm counterweights removed;

Fig. 4 represents a detail showing the actuation of the feed arm by the dog; and

Figs. 5 and 6 represent details showing the position before and after release of the feed arm by the dog, Fig. 5 being a partial section taken on line 5—5 of Fig. 4.

Referring now to the drawings, the reference character 10 designates a base member, provided with pairs of converging arms 12, there being one pair at each end of the base member. Each pair of arms 12 is preferably joined together at the top as at 14 to form a support for bearings 16 to receive shaft 18. As shown in the drawings the

shaft 18 is reduced in diameter at 20 to form shoulders 22 which abut bearings 16 to hold the shaft in place but other means may be used. Mounted on the shaft 18 and secured thereto are driving arms 24 provided with striking heads 26 at one end and counterweights 28 at the other end. A pulley 30 is secured to the shaft 18 and is driven by belt 32 which runs over the drive pulley 34. Drive pulley 34 is secured to a shaft 36 which is connected with a flexible cable 38 which may be driven by an electric motor or other suitable means.

I may drive the cable 38 from the engine of an automobile or truck by connecting the cable 38 to the front of an automobile where the engine is usually cranked or I may drive it by electricity. An idler pulley 42 is provided for tensioning belt 32 and thereby starting the rotation of shaft 18 after pulley 34 is rotating. This pulley 42 is rotatably mounted on stub shaft 44 connected to vertical arm 46 which in turn is connected to one end of horizontal arm 48. Arm 48 is mounted in bearings 52 and 54. Connected to the other end of arm 48 is an operating lever 56 having a spring pressed arm 58 for cooperation with a toothed segment 59 secured to one of the arms 12. The spring pressed arm 58 holds the lever in adjusted position. By moving the lever in one direction, the idler pulley may be brought to bear against belt 32 to start the rotation of shaft 18 and movement of the lever in the other direction permits stopping rotation of the shaft 18. The pulley 34 may be brought to any suitable speed by connecting cable 38 with a source of power and with the idler pulley 42 in inoperative position so that no power is transmitted to shaft 18 by the belt. After such speed is attained then the idler pulley is moved gradually into operative position against belt 32 to cause tightening of the belt 32 on the pulleys and transmission of power from drive pulley 34 to pulley 30. Rotation of pulley 30 causes rotation of shaft 18 and of the driving arms 24. The speed of rotation is preferably observed by a speed indicator 60 connected to the shaft 18 by a flexible cable 61. This indicator may be provided with any suitable indicia. Pulley 30 may be so made as to serve as a flywheel.

Cooperating with the striking heads 26 on arms 24 are rotatable tee arms 62 whose speed is synchronized with the speed of the arms 24 so that the head 26 hits the ball on a tee arm in exactly the proper position of the rotating tee arm. In Fig. 4 at 63 I have shown the position of a ball as the arm moves through the striking position

5 during its previous rotation, the ball moving from position 63 to striking position 64 while the driving arm makes one rotation. The dot and dash line 65 represents the plane of rotation of one of the arms 24. Each tee arm is banked as at 10 66 so that there is no tendency for the ball to leave the tee at the maximum speed at which the tee arm rotates until such a time as the driving arm knocks it from the tee. These tee arms are 15 driven from shaft 18 through a worm gearing and another shaft to be now described. Each tee arm 62 is secured to a vertical shaft 67 having its lower end rotatably mounted in a bottom bearing 68 and its upper end rotatably mounted in top bearing 70 20 suitably secured to the top of converging arms 12 of the frame. Secured to the upper end of each shaft 67 is a worm gear 74 which meshes with a worm 76 secured to each end of the shaft 18. The ratio of the worm to the worm gear is 25 20 to 1 so that each driving arm rotates twenty times to one rotation of each tee arm.

With the driving arms and tee arms rotating, it is necessary to feed balls to the tee arms and for this purpose I have provided a feed arm for 25 each tee arm. This feed arm 79 (see Figs. 2 and 3) is loosely mounted on eccentric collar 80 mounted on but not secured to vertical shaft 67. Collar 80 is secured to a bracket 81 secured to one of the vertical arms 12. Each feed arm 79 has a claw 30 82 on the outer end thereof on which the ball to be tested is rested. Normally each feed arm is held against stop 84 provided on bracket 81 by spring 88.

For placing a ball on the tee arm, the feed arm is rotated for about a quarter of a turn and for moving the feed arm through such an arc, a dog 90 is secured to shaft 67 above the feed arm. This dog is provided with a downwardly projecting arm 92 which is adapted to abut a portion of the feed arm and move it through an arc of a circle. It will be noted the feed arm 79 is mounted at an angle to the shaft on the eccentric collar 80 at an angle to the shaft but around the same center so that after a partial 45 rotation, the feed arm moves down away from the dog and will slip away from the downwardly projecting arm 92. The feed arm is then free of the dog and is returned to its normal position against stop 84 by the spring 88. The dog 90 is so positioned during the actuation of the feed arm that the feed arm and the tee arm will be in alinement and will be rotated in unison through an arc of a circle and during this rotation the feed arm, due to its angular mounting, will gently 50 place or deposit the golf ball from its claw onto the exact center of the tee. After such deposition the feed arm is released by the arm on the dog and slips under the downwardly projecting arm 92 of the dog 90 and is returned to its original 55 position by the spring 88.

The operation of the apparatus shown in the drawings will now be described. With the idler pulley 42 in inoperative position the flexible cable 38 is connected with a source of power such as an automobile engine or an electric motor to cause 60 rotation of pulley 34. When the speed of the pulley 34 is relatively low, the idler pulley 42 is gradually brought into position against the belt 32 to cause rotation of pulley 30 and driving arms 70 24. Rotation of the shaft 18 causes rotation of the worms 76 which mesh with worm gears 74 to cause rotation of vertical shafts 67. The shafts 67 rotate at about 1/20th the speed of the rotation of the driving arms. The tee arms 62 and 75 the dogs 90 being secured to the shafts 67 are

rotated therewith. Due to the gearing 14, 76, the rotations of driving arms 24 and tee arms are synchronized so that the tee arms with the golf balls therein are in proper position for the balls to be struck by the driving arms during the 5 operation of the apparatus.

The speed of rotation is read on indicator 60 and when proper speed of the driving arms is obtained, the apparatus is ready for the testing of golf balls. Different makes of golf balls may 10 be subjected to comparative tests by simultaneously using one make of ball on one side of the device and another make of ball on the other side of the device, or only one side of the device may be used. A device having only one driving arm 15 may be used. While the parts of the apparatus are moving, the selected golf balls are placed in in the claws 82 of the feed arms 79. As the shafts 67 rotate, the tee arms 62 and dogs 90 will also be rotated and as the dogs 90 rotate they carry the 20 arms 79 with them and the feed arms are moved in the arc of a circle for about a quarter of a turn. During this movement each feed arm 79 and tee arm 62 are substantially in vertical alinement so that the golf ball is placed or deposited 25 from the feed arm on the tee arm during this rotation. Each feed arm 79 is loosely mounted on the eccentric collar 80 on shaft 67 so that as the feed arm is moved in the arc of a circle its angularity is changed and it moves down and 30 slips away underneath the arm 92 on the dog 90. This release of the feed arm 79 is brought about after the golf ball is properly placed on the tee arm. After its release the feed arm is returned to its original position by spring 88. 35

I will now give a specific example of the operation of a device made according to the invention as shown in the drawings, but I am not to be restricted thereto. The speed at which I operated this device was about 650 R. P. M. of 40 the driving arms and at this speed I have knocked golf balls 450 yards carry. At this rate there were 20 golf balls per minute knocked from each side of the apparatus or device which means that a golf ball was knocked into the air every 45 three seconds, and several golf balls were in the air at the same time from both sides of the machine. As one form of speed indicator I may use an ordinary automobile speedometer which is connected to the end of shaft 18 and this 50 speedometer can be calibrated to indicate the number of revolutions per minute.

It is to be understood that the foregoing embodiments are given only by way of illustration and that the same may be modified in many 55 particulars without departing from the spirit of my invention.

What I claim is:

1. A device of the character described, including, in combination, supporting means, a plurality of driving arms rotatably mounted thereon for simultaneous movement, means for rotating said arms and including vertical rotatable shafts, rotatable tee arms secured to each of said shafts and adapted to hold golf balls 65 to be struck by said driving arms, the rotation of said tee arms and said driving arms being synchronized, and means for placing golf balls on said tee arms while said tee arms are rotating.

2. A device of the character described, including, in combination, a supporting means, a driving arm rotatably mounted thereon, means for rotating said arm including a vertical rotatable shaft, a rotatable tee arm secured to said shaft and adapted to hold a golf ball to be 70 75

struck by said driving arm, and means for placing a golf ball on said tee arm while said tee arm is rotating, said placing means including a feed arm mounted on said shaft for oscillation.

3. A device of the character described, including, in combination, supporting means, driving arms rotatably mounted thereon for simultaneous movement, means for rotating said arms and including vertical rotatable shafts, rotatable tee arms secured to said shafts and adapted to hold golf balls, and means for placing golf balls on said tee arms while said tee arms are rotating, said placing means including feed arms mounted on said shafts for oscillation and dogs secured to said shafts for actuating said feed arms to move said arms for a distance to deposit golf balls on said tee arms while said tee arms are rotating.

4. A device of the character described, including, in combination, supporting means, a plurality of driving arms rotatably mounted thereon for simultaneous movement, means for rotating said arms and including vertical rotatable shafts, rotatable tee arms secured to said shafts and adapted to hold golf balls to be struck by said driving arms simultaneously for comparison, the rotations of said tee arms and said driving arms being synchronized, and means for placing golf balls on said tee arms while said tee arms are rotating, said placing means including feed arms mounted on said shafts for oscillation in a plane at an angle to the horizontal, and dogs secured to said shafts for actuating and moving said feed arms for a distance to deposit golf balls on said tee arms while said tee arms are rotating, said feed arms being mounted to rotate at an angle to the horizontal so that said dogs release said feed arms after a predetermined amount of oscillation and after the golf balls are deposited on said tee arms.

5. A device of the character described, including, in combination, supporting means, a plurality of driving arms rotatably mounted thereon for simultaneous movement, means for rotating said arms and including vertical rotatable shafts, rotatable tee arms secured to said shafts and adapted to hold golf balls to be struck by said driving arms simultaneously for comparison, the rotations of said tee arms and said driving arms being synchronized, and means for placing golf balls on said tee arms while said tee arms are rotating, said placing means including eccentric collars mounted on said vertical shafts but held from rotation, feed arms mounted on said eccentric collars for oscillation in a plane at an angle to the horizontal, said feed arms having claws at their ends for receiving golf balls, dogs secured to said vertical shafts for actuating and moving said feed arms a distance to deposit golf balls on said tee arms and then for releasing said feed arms after a predetermined amount of oscillation and after the golf balls are deposited on said tee arms.

6. A device of the character described, including, in combination, supporting means, a plurality of driving arms rotatably mounted thereon for simultaneous movement, means for rotating said arms and including vertical rotatable shafts, rotatable tee arms secured to said shafts and adapted to hold golf balls to be struck by said driving arms simultaneously for comparison, the rotations of said tee arms and said driving arms being synchronized, and means for placing golf balls on said tee arms while

said tee arms are rotating, said placing means including eccentric collars mounted on said vertical shafts but held from rotation, feed arms mounted on said eccentric collars for oscillation in a plane at an angle to the horizontal, said feed arms having claws at their ends for receiving golf balls, dogs secured to said vertical shafts for actuating and moving said feed arms a distance to deposit golf balls on said tee arms and then for releasing said feed arms after a predetermined amount of oscillation and after the golf balls are deposited on said tee arms and spring means for returning said feed arms to their original positions for the next actuation.

7. A device of the character described, including, in combination, supporting means, a plurality of driving arms rotatably mounted thereon for simultaneous movement, means for rotating said arms and including vertical rotatable shafts, rotatable tee arms secured to said shafts and adapted to hold golf balls to be struck by said driving arms simultaneously for comparison, the rotations of said tee arms and said driving arms being synchronized and means for placing golf balls on said tee arms while said tee arms are rotating, said placing means including eccentric collars mounted on said vertical shafts but held from rotation, feed arms mounted on said eccentric collars for oscillation in a plane at an angle to the horizontal, said feed arms having claws at their ends for receiving golf balls, dogs secured to said vertical shafts for actuating and moving said feed arms a distance to deposit golf balls on said tee arms and then for releasing said feed arms after a predetermined amount of oscillation and after the golf balls are deposited on said tee arms, the tee on said tee arms being banked to prevent the deposited golf ball from being thrown from said tee arm before it is struck by one of said driving arms.

8. A device of the character described, including, in combination, supporting means, a driving arm rotatably mounted thereon, means for rotating said arm, a rotatable tee arm adapted to hold a golf ball, and means for placing a golf ball on said tee arm while said tee arm is rotating, said means including a feed arm mounted to oscillate and to move with said tee arm for a distance to deposit a golf ball on said tee arm and then to return to position for the next oscillation.

9. A device of the character described, including, in combination, supporting means, a driving arm rotatably mounted thereon, means for rotating said arm, a rotatable vertical shaft associated with said driving arm, a rotatable tee arm secured to said vertical shaft and adapted to hold a golf ball, and means for placing the golf ball on said tee arm while said tee arm is rotating, said means including an eccentric collar held from rotation and a feed arm mounted at an angle on said collar for oscillation and for movement with said tee arm for a distance to move down and deposit a golf ball thereon.

10. A device of the character described, including, in combination, supporting means, a driving arm rotatably mounted thereon, means for rotating said arm, a rotatable vertical shaft associated with said driving arm, a rotatable tee arm secured to said vertical shaft and adapted to hold a golf ball, and means for placing the golf ball on said tee arm while said tee arm is rotating, said means including an eccentric collar held from rotation, a feed arm mounted at an angle on said collar for oscillation, said feed arm hav-

ing a ball-receiving claw, a dog secured to said vertical shaft for moving said feed arm with said tee arm for a distance so as to deposit a golf ball on said tee arm, said feed arm due to its eccentric mounting moving away from said dog to be released after the golf ball is deposited.

11. A device of the character described, including, in combination, supporting means, a driving arm rotatably mounted thereon, means for rotating said arm, a rotatable vertical shaft associated with said driving arm, a rotatable tee arm secured to said vertical shaft and adapted to hold a golf ball, and means for placing a golf ball on said tee arm while said tee arm is rotating, said means including an eccentric collar held from rotation, a feed arm mounted at an angle on said collar for oscillation, said feed arm having a ball-receiving claw, a dog secured to said vertical shaft for moving said feed arm with said tee arm for a distance so as to deposit a golf ball on said tee arm, said feed arm due to its eccentric mounting moving away from said dog to be released after the golf ball is deposited, and means for returning said feed arm to its original position where a golf ball to be tested is placed in the claw thereof.

12. A device of the character described, including, in combination, supporting means, a driving arm rotatably mounted thereon, a shaft for rotating said driving arm, a vertical rotating shaft, a rotatable tee arm secured to said vertical shaft and adapted to hold a golf ball, gears between said shafts for rotating said driving arm and said tee arm in synchronism whereby said driving arm is rotated an even

number of times for each rotation of said tee arm and said tee arm is in correct position when said driving arm is in striking position.

13. A device of the character described, including, in combination, supporting means, a driving arm rotatably mounted thereon, a shaft for rotating said driving arm, a vertical rotatable shaft, a rotatable tee arm secured to said vertical shaft and adapted to hold a golf ball, gears between said shafts for rotating said driving arm and said tee arm in synchronism whereby said driving arm is rotated an even number of times for each rotation of said tee arm and said tee arm is in correct position when said driving arm is in striking position and means for placing or depositing a golf ball on said tee arm while said tee arm is rotating.

14. A device of the character described, including, in combination, supporting means, a driving arm rotatably mounted thereon, a shaft for rotating said driving arm, a vertical rotatable shaft, a rotatable tee arm secured to said vertical shaft and adapted to hold a golf ball, gears between said shafts for rotating said driving arm and said tee arm in synchronism whereby said driving arm is rotated an even number of times for each rotation of said tee arm and said tee arm is in correct position when said driving arm is in striking position and means for placing or depositing a golf ball on said tee arm while said tee arm is rotating, said last mentioned means including a feed arm mounted for oscillation in a plane at an angle to the horizontal.

PHILIP E. YOUNG. 35
